Primary Examiner — Barbara Fox*Assistant Examiner* — Dana K Weiland(74) *Attorney, Agent, or Firm* — Fish & Richardson P.C.(57) **CLAIM**

The ornamental design for a tablet computer enclosure with card swipe, substantially as shown and described.

DESCRIPTION

FIG. 1 is a perspective view of a tablet computer enclosure with card swipe showing the new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings represent portions of the tablet computer enclosure with card swipe that form no part of the claimed design.

1 Claim, 4 Drawing Sheets(56)
